corporation of New York

Application July 20, 1954, Serial No. 444,459

4 Claims. (Cl. 62—152)

This invention relates to improvements in a steam vacuum refrigeration or flash system of the barometric type.

The invention provides a barometric type refrigeration system wherein a tank unit has a flash tank and seal tank combined for support on a single foundation. A multi-stage ejector and condenser system is connected in series with the flash tank for maintaining a desired vacuum for cooling liquid in the flash tank. Barometric leg pipes connect the condensers with the seal tank portion of the unit and cooperate with the connected series of ejectors, condensers and tank unit carried supporting means to support the parts forming the system on the tank unit for improved construction, assembly, operation and control.

The combined flash and seal tank unit provides for the use of a rounded partition member to form the bottom of the flash tank for better drainage, cleaning and stress distributing cooperation with the shell. This partition member has a tubular peripheral portion which facilitates positioning and assembly in the single shell in forming the combined tank unit. This also enables a flat base plate to be used on the bottom of the shell in supporting the tank unit as well as cooperating with the partition member in providing the seal tank at the bottom. By combining the flash and seal tanks in a single tank unit a saving in cost of construction is achieved by the invention with the added advantages of fabrication in the factory, reduction in material, and elimination of material and labor in erection at the point of use.

By employing the combined flash and seal tank unit, the invention provides for direct connection of the barometric leg pipes with the unit for improving the construction of the complete refrigeration unit by cooperating with the ejectors in supporting the condensers and eliminating the necessity for other supports.

In the drawings:

Fig. 1 is a side elevation showing an assembled barometric type steam vacuum refrigeration unit with portions broken away and shown in cross section to illustrate details of construction.

Fig. 2 is a top plan view of the unit shown in Fig. 1.

Fig. 3 is a view similar to Fig. 1, showing the unit in a position rotated clockwise approximately one hundred twenty degrees from that shown in Fig. 1.

Fig. 4 is a horizontal cross section taken on line 4—4 of Fig. 3.

The refrigeration assembly has a combined flash and seal tank unit 1 formed of a tubular shell 2 of cylindrical shape as shown in the drawing. Shell 2 has the lower end seated on base plate 3 and welded or otherwise secured thereto in liquid-tight relation. A cap 4 is rigidly mounted on the upper end of shell 2 in tightly sealed relation. A partition member 5, as shown in Fig. 3, is mounted intermediate the ends of shell 1 in the lower end portion thereof. Partition member 5 has a peripheral portion 6 of substantially cylindrical shape for slidably engaging the inner wall surface of shell 1. One edge

2

of portion 6 is integral with a transverse wall 7 formed of partially spherical shape, as shown in Fig. 3, so the central portion is lower than the edges. Peripheral portion 6 is welded or otherwise suitably secured to shell 1 in fluid-tight relation to form a flash tank 8 in the upper portion of the shell and a seal tank 9 in the lower end.

The tank unit 1 has a chilled water return 10 at the upper end extending into flash tank 8 where the end is equipped with a water distributing cone 11 for spraying water or other liquid used in the flash tank for vaporizing and cooling in a well known manner. Shell 2, near the bottom of flash tank 8, is provided with a chilled water outlet 12 and a manhole 13 for entrance to the interior of the flash tank for cleaning and repair purposes. A flash tank drain 14 is connected to the lower central portion of transverse wall 7 of partition member 5 and extends through the upper portion of the seal tank outwardly through shell 2, as shown in the drawing.

Shell 2 has vent holes 15 at the upper end of the seal tank portion below partition member 5. A foundation 16, preferably of reinforced concrete is constructed to carry the weight of the complete assembled refrigeration unit. Foundation 16 has a flat top surface for receiving base plate 3 of tank unit 1 usually at a convenient distance above the adjacent ground surface. Shell 2 has drain 17 at the lower end communicating with the seal tank on one side of a transverse overflow weir 18 for draining off cooling water and water of condensation. A manhole 19 provides access to the interior of the seal tank for inspection, cleaning and repair.

Cap 4 is provided with a flanged supporting bracket 20 projecting upwardly from the central portion. A tubular supporting pipe 21 is attached to bracket 20 and extends upwardly above the tank unit in coaxial relation. Pipe 21 supports primary barometric condenser 22 on the upper end in coaxial relation and forms the upper portion of the barometric leg for conducting condensate from the condenser to seal tank 9. A primary condenser barometric leg pipe 23 is connected to supporting pipe 21 above bracket 20, extends outwardly and then downwardly outside of the tank unit to the lower end where it is connected to shell 2 near the bottom of seal tank 9. Water of condensation and condensing water is conducted by supporting pipe 21 and primary condenser barometric leg pipe 23 from primary condenser 22 to seal tank 9. Pipes 21 and 23 function as the barometric leg for the primary condenser in maintaining the difference in water level therein in comparison with that in seal tank 9, a minimum of approximately thirty-four feet, for maintaining the usual functioning of the primary condenser in maintaining reduced pressure in the flash tank. Barometric leg pipe 23 in having both the upper and lower ends attached to supporting pipe 21 and shell 2, respectively, with the seal tank combined in a single unit with the flash tank results in a saving in material, lower cost of construction and assembly, reinforcement of the assembled unit, and more accurate determination of the tank unit and pipe sizes and lengths for a given capacity refrigeration system.

A primary ejector or booster 24 has the lower end mounted on the upper end of flash tank 1 by attachment to shell 2 in communication with flash tank 8. The primary ejector is attached at the upper end to and communicates with the upper portion of primary condenser 22, as shown in Fig. 1. Primary ejector 24 is of conventional construction having the usual steam inlet and nozzle in the lower end and exhausting into the primary condenser, also of conventional construction. A condensing water inlet 25 is connected to primary condenser

22 and a suitable source of supply, for discharging water or other condensing liquid in the primary condenser from distributing cone 26, as shown in Fig. 3. The water from cone 26 condenses steam in the primary condenser with the condensate and condensing water being drained off through pipes 21 and 23, as above stated.

Vacuum is maintained in primary condenser 22 by a second or intermediate ejector 27 connected to the upper end. Ejector 27 discharges into a second condenser 28. Water or other cooling liquid is sprayed into condenser 28 from a suitable source for condensing the vapor withdrawn from primary condenser 22 in maintaining the desired degree of vacuum. Second ejector 27 and condenser 28 are both supported at one side of and attached to primary condenser 22. A second condenser barometric leg pipe 29 is connected to second condenser 28 at the upper end and to the lower end of shell 2 in communication with seal tank 9. Water of condensation and cooling water is conducted to the seal tank by pipe 29 which forms the barometric leg for secondary or inter-condenser 28.

A final or third ejector 30, Fig. 1, is connected to second condenser 28 for maintaining a suitable vacuum therein and has an exhaust pipe 31 connecting its discharge end to the lower end of shell 2. Pipe 31 has the lower end extending into seal tank 9 with discharge end 32 located adjacent overflow weir 18. The overflow liquid contacts the discharge end for condensing steam exhausting therefrom and cooperates to create a suction for withdrawing steam from final ejector 30.

The inter-condenser 28 has a condensing water inlet and spraying means of conventional form. The second and third ejectors have the usual steam nozzles therein. Control valves are used to control the supply of steam to the several ejectors and condensing water to the condensers in a conventional and well known manner.

A safety ladder and one or more platforms, not shown, and of conventional form, may be secured to the assembled unit so manual access is provided for operation of the various control valves for starting, stopping and maintaining the desired operation of the unit. Gauges and other conventional equipment may be applied in the usual locations on the assembled unit for indicating the information desired for the control and operation of the complete unit according to the results desired.

In constructing tank unit 1, transverse wall 18, partition member 5 and base plate 3, cooperate to provide stress reducing cooperation for enabling the use of lighter gauge sheet metal with efficient stress distribution on base plate 3, so the unit efficiently retains its shape in carrying and distributing the load to foundation 16.

In operation, the various controls are actuated to maintain the desired cooling liquid level in the flash tank, the desired operation of each of the ejectors and condensers to maintain a vacuum in the flash tank for cooling the liquid to the required temperature. The cooling liquid in the flash tank is circulated to apparatus, not shown, for producing the desired refrigerating operation. All water of condensation and condensing water is collected in the seal tank in maintaining the barometric leg operation with the condensers and ejectors in a single self-contained unit structure mounted on a single foundation. Excess cooling water and condensate is discharged from a single outlet or drain 17 at the bottom of the tank unit for such subsequent use as may be made according to well known teachings in the art.

The invention claimed is:

1. A steam vacuum refrigeration unit for support on a single substantially solid foundation, comprising a seal tank mounted on said foundation, a flash tank mounted in superimposed vertically aligned relation on said seal tank, a supporting member extending vertically from the top central portion of said flash tank, a primary barometric condenser mounted in vertically extending relation on the upper end of said supporting member, a pipe forming a primary condenser barometric leg connected at the upper end for communication with the lower end of

said primary condenser and connected at the lower end to the lower portion of said seal tank and providing communication between said seal tank and primary condenser, a primary ejector connected to said flash tank and primary condenser for maintaining a vacuum in said flash tank for cooling liquid therein, a secondary condenser adjacent said primary condenser, a secondary ejector connected with said primary and secondary condensers for normally maintaining a vacuum in said primary condenser, a secondary barometric leg pipe connected at the upper end to the lower portion of said secondary condenser and having the lower end connected to the lower portion of said seal tank for establishing communication therebetween, and means for maintaining a vacuum in said secondary condenser, whereby said flash and seal tanks with said attached supporting member, primary and secondary condensers, primary and secondary ejectors and said primary and secondary barometric leg pipes cooperate in supporting one another in forming an integral assembled refrigeration unit.

2. In a barometric condenser type of steam vacuum refrigeration wherein a three-stage series of steam ejectors is interconnected with primary and secondary barometric condensers in which the primary condenser is supported above the flash tank, the combination of a supporting tank unit formed of a seal tank at the lower end having a base plate for supporting the unit on a foundation, a flash tank above said seal tank forming the upper end of said tank unit with said primary condenser supported on and above the upper end thereof, and primary and secondary barometric leg pipes connected to said tank unit at the lower end in communication with said seal tank and having connection at the upper ends with said primary and secondary condensers, respectively, whereby said pipes and tank unit cooperate to support said condensers with said steam ejectors in interconnected relation in forming a complete interconnected tank unit supported refrigeration unit.

3. In a barometric condenser type of steam vacuum refrigeration wherein a three-stage series of steam ejectors are interconnected with a flash tank, primary and secondary condensers in series relation for cooling fluid in the flash tank, the combination of a tank unit having a tubular upright shell, a base plate secured on the lower end of said shell for supporting said unit on a foundation, a cap closing said shell at the upper end, and a partition wall in said shell between the upper and lower ends dividing said shell into an upper flash tank and a lower seal tank, said tank unit having said primary condenser supported on and above said unit on said cap, the first of said three-stage series of steam ejectors being connected to said flash tank portion of said unit and said primary condenser, and a plurality of substantially vertically extending spaced pipes connected to said seal tank at the lower end and at the upper end to said primary and secondary condensers and the last stage of said series of steam ejectors, whereby said pipes cooperate in supporting said ejectors and condensers above said tank unit in rigid cooperative relation to form a complete refrigeration assembly for refrigerating liquid in said flash tank and collecting condensate in said seal tank in maintaining uniform operation of barometric legs for said condensers through said pipes.

4. In a barometric condenser type of steam vacuum refrigeration wherein a plurality of steam ejectors and condensers in series relation normally maintain a vacuum in a flash tank, the combination of a tank unit having a vertically extending tubular shell, a substantially flat base plate secured in liquid-tight relation on the lower extremity of said shell and supporting the assembled unit, a cap closing the upper end of said shell in fluid-tight relation, a partition member dividing said shell into an upper flash tank portion and a lower seal tank portion having a tubular peripheral portion fitting the inner surface of said tubular shell intermediate the ends of said

shell and sealed thereto in fluid-tight relation and having a downwardly curved portion extending inwardly from said peripheral portion to the central portion thereof, said ejectors and condensers being connected to and supported by said tank unit, and barometric leg pipes connecting said condensers with said seal tank portion of said tank unit and also cooperating in supporting said condensers on said tank unit.
